DRAINER BASKET

Benjamin F. Miller, Darien, Conn., assignor to Artistic Wire Products Company, Incorporated, East Hampton, Conn., a corporation of Connecticut

Application September 22, 1959, Serial No. 57,646

Term of patent 14 years

(Cl. D44—29)

Fig. 1 is a plan view of a drainer basket embodying my new design.

Fig. 2 is an elevational view of one end of said basket, the opposite end being a substantial mirror image thereof.

Fig. 3 is a perspective, front view of said basket.

Fig. 4 is a sectional end view of said basket on line 4—4 of Fig. 5.

Fig. 5 is an elevational rear view.

The dominant features of my new design reside in the portions shown in full lines.

I claim:

The ornamental design for a drainer basket, as shown and described.
